US00D746246S

(12) **United States Design Patent**
Park

(10) **Patent No.:** **US D746,246 S**
(45) **Date of Patent:** ** *Dec. 29, 2015

(54) **MOBILE TERMINAL**

(71) Applicant: **Samsung Electronics Co., Ltd.**,
Suwon-si (KR)

(72) Inventor: **Seon-Keun Park**, Seoul (KR)

(73) Assignee: **Samsung Electronics Co., Ltd.**,
Suwon-si (KR)

(*) Notice: This patent is subject to a terminal disclaimer.

(**) Term: **14 Years**

(21) Appl. No.: **29/465,088**

(22) Filed: **Aug. 23, 2013**

(30) **Foreign Application Priority Data**

Feb. 23, 2013 (KR) 30-2013-0009487

(51) **LOC (10) Cl.** **14-03**

(57) **CLAIM**

The ornamental design for a mobile terminal, as shown and described.

DESCRIPTION

FIG. 1 is a front perspective view of a mobile terminal showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a rear perspective view thereof.

The broken lines shown in the figures that are within the claimed surface, are immediately adjacent to the shaded areas, and define regions that are unshaded, represent the bounds of the claim, while all other broken lines are directed to environment. The broken lines form no part of the claimed design.

1 Claim, 6 Drawing Sheets
